AGUR JUDSON AND STEPHEN A. FARRINGTON, OF NEWARK, NEW JERSEY.

Letters Patent No. 92,057, dated June 29, 1869.

IMPROVEMENT IN HYDRAULIC PRESSES.

The Schedule referred to in these Letters Patent and making part of the same.

To all whom it may concern:

Be it known that we, AGUR JUDSON and STEPHEN A. FARRINGTON, both of the city of Newark, county of Essex, and State of New Jersey, have invented certain Improvements in Hydraulic Presses; and we do hereby declare that the following, taken in connection with the drawings which accompany and form part of this specification, is a description of our invention sufficient to enable those skilled in the art to practise it.

Our improvements relate to that class of hydraulic (or other power) press, in which is to be compressed a series of flat articles, laid upon a series of plates, one above the other, in such manner, that when the power is applied, each plate in succession is pressed against the next, until the whole of the series is placed under pressure to the degree and for the length of time desired.

In such presses, as heretofore constructed, the several plates are linked or connected together in such manner, that when the pressure is removed from beneath, each plate will hang suspended from the one next above it, a distance equal to the length of the link, or other means of suspension, this separation of the plates from each other being necessary, in order to facilitate the removal therefrom of the articles pressed, and for the substitution of others to be pressed.

Such a construction is found to entail certain difficulties and expense, and delays in the removal of a plate, for repairs or otherwise, which it is the object of our invention to avoid.

We have illustrated our invention, applied to a press such as is now used in linseed-oil factories, for the purpose of pressing the oil from the seed, or rather from the "cake," so called, and for which purpose it is more especially designed, although, as will be evident, equally adapted for any similar or kindred purpose.

In the drawings—

Figure 1 represents a central vertical section of a press, with our improvements applied thereto;

Figure 2, a fragmentary view of the same, the red lines indicating the position of the parts when the "cakes" are under pressure; and

Figure 3, one of the plates detached from the press.

A indicates the frame of the press;

B, the shaft or spindle, which, by hydraulic or other power, imparts in its upward motion the pressure required; and

C, the bed surmounting the shaft.

These parts may be of any ordinary construction.

D, &c., are the plates or pans, which, when the liquid to be expressed is valuable, and to be saved, are made so as to contain it, and permit its discharge at a proper mouth or lip, as shown at d.

They are made, it will be seen, complete each in itself as a simple pan, having no connection or means of connection whatever with any other pan of the series.

E are the ordinary vertical guide-ways, in which ride the corners of each plate or pan, as it is moved up or down.

F, &c., are weighted levers, nearly right-angled in shape, having weights, f, at the end of their outer arms, sufficient to bear inwards, towards the edge of the plates, the lower or hooked end g.

A swell, h, is also made on the inner edge of each lever F, of such protuberance that when it bears against the edge of one of the plates, it will cause the hook on the same lever to stand off and out of contact with the plate or plates beneath, the lever being so hung, and a stop-pin, i, for each being so located, that when such swell is not in contact with a plate, the hook, by the force of the weight f, will be permitted to move inward far enough to pass under the plate, and form a rest on which it will be supported.

A set of these hooks being applied to each corner of the frame, in such positions that every plate may, as shown in fig. 1, rest at each corner upon a hook, and so that when pressure is applied to the press, each plate is unobstructed in its upward movement, as will be plainly seen by reference to fig. 2, it will be observed that the arrest of the several plates, at proper and equal distances, by the hooks, is automatic and certain.

With such a construction, whenever a plate or pin may become warped or bent, or in any way damaged, any one separately may be readily removed, without disturbing the harmony or efficiency of the remainder in their true action, by simply unscrewing and removing, for the moment, from one side of the machine, two of the vertical guides, and then withdrawing the loose plate.

Upon replacing the guides, the apparatus is at once ready again for use.

It will be seen, that when the plates are all compressed together, as shown in fig. 2, and the pressure is taken off, and the plates descend, the top one only of the compact series is first caught and held by the hooks, for the reason that there is no plate above it, to act on the swells h, and force the hooks outward against the action of the weights.

When the top plate is thus caught and held, the next plate beneath will have passed below the swells of the next set of levers, and there will be nothing to prevent their hooks, in a similar manner, from moving inward, and catching and detaining the next plate, and this action is thus repeated throughout the series.

It is evident that springs might be employed, to perform the duty of the weights, but we do not deem them so simple or efficient for the purpose.

The shape of the levers may also be varied, as de-

sired, without departing from the spirit of our invention, and pins thereon might serve for hooks, the essential features of our invention being that the levers shall be so shaped and actuated, that they shall automatically catch and hold the plates when desired, and refuse to take and hold them when not desired, and also, that each plate shall be entirely disconnected from the others.

We claim the self-acting levers, having the swell and hook, or their equivalents, thereon, the swell having a prominence exceeding that of the hook, when

the lever is used in combination with a plate, D, substantially as shown and described.

We also claim a series of disconnected plates, combined with a series of self-acting hook-levers, constructed substantially as described.

AGUR JUDSON.

STEPHEN A. FARRINGTON.
